(57) **CLAIM**

The ornamental design for a drain hose as shown and described.

DESCRIPTION

FIG. 1 is a perspective view of a drain hose showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion 9 shown in FIG. 1. The dash-dash broken lines in the drawings depict portions of the drain hose that form no part of the claimed design. The dot-dash broken lines represent boundaries of the enlarged portions and form no part of the claimed design. The dash-dot-dot broken lines overlaying the drain hose are symbolic break-away lines. Any portion of the drain hose between the break-away lines forms no part of the claim design.
